UNITED STATES PATENT OFFICE.

CHARLES ALBERT KELLER, OF PARIS, FRANCE.

ELECTRIC FURNACE.

SPECIFICATION forming part of Letters Patent No. 688,861, dated December 17, 1901.

Application filed December 3, 1900. Serial No. 38,496. (No model.)

To all whom it may concern:

Be it known that I, CHARLES ALBERT KELLER, a citizen of the Republic of France, residing in Paris, France, have invented certain new and useful Improvements in Electric Furnaces, Embodied in an Electric Furnace with Two Movable Electrode-Carriages, of which the following is a specification.

My invention relates to improvements in electric furnaces; and the object of these improvements is to obviate the inconveniences inherent to the said furnaces as they were used heretofore.

In order to make my invention well understood, it is necessary to shortly review the arrangement of the electric furnaces as they are now in use. In most of these furnaces one or more movable electrodes placed in a vertical, horizontal, or slanting position are used in such a way that part of them is outside and part inside the furnace. The end of that part of the electrode which is inside the furnace is either immersed in the matter in fusion or immediately above. As a consequence of this arrangement the part of the electrode inside the furnace reaches a very high temperature, and this high temperature is communicated by the calorific conductivity to the part of the electrode outside the furnace to an extent sufficient to produce a slow combustion of this part of the electrode through its contact with the oxygen of the air. This combustion causes a rapid enfeeblement of the said section of the electrode, so that the latter breaks at this place when only twenty or thirty per cent. of its full length has been used; but there is still another inconvenience, at least with those furnaces where the movable electrodes are placed vertically—namely, the working of the furnace has to be interrupted as soon as the mass to be treated reaches a certain level, for otherwise the furnace might be damaged in its upper part if it is a covered furnace, and at any rate the mass already treated would on account of the height of its level cause a loss of energy resulting from the introduction of its ohmic resistance into the electric circuit. Moreover, when the movable vertical electrode becomes rather short by its being burned up to such a point the metallic pieces serving for the fastenings and connections are

very often deteriorated because of their being brought too near the heat zone.

Now the object of my invention is to avoid these grave inconveniences. I attain this object by placing the electrodes completely inside the furnace, the electrodes being held by two movable sockets, wherein the fastenings and connections are arranged so that they are kept separate from the seat of the heat, so that they cannot be reached by the deteriorating action of the latter.

The furnace shown in the accompanying drawings embodies my invention.

Figure 1 is a longitudinal section of the said furnace. Fig. 2 is a plan view of the same as it is represented in Fig. 1. Fig. 3 is a cross-section of the same on the line A B of Fig. 1. Fig. 4 is a longitudinal section of one of the movable electrode carriers or sockets, and Fig. 5 is a plan view of the latter.

The floor of the furnace is formed of two equal carriages bearing the electrodes, Fig. 1. The latter consist of a certain number of carbon blocks *l*, preferably of a square section, which are placed on the metallic bottom of the carriage, whose upper part is formed of a vaulted ceiling provided with apertures of the same section as the carbon blocks, *80* whose heads project a suitable distance through said apertures in the upper part of the carriage. The said ceiling of the carriage is formed of two arches *a a*, made of refractory bricks, the arches leaning on one side *85* against a metallic central piece *b* of suitable form and on the other side against the walls *c c*. A filling of refractory material (represented at *w*) may be employed to level the tops of the arches. On the emerging heads *90* of the carbon blocks *l* are placed the small carbon sticks *d* without any fastenings. In this way the electric contacts are completely separated from the fusion-hearth, and the calorific conductivity of the parts separating them therefrom is reduced to a minimum, so that those contacts are kept at the lowest temperature which it is possible to obtain for them. To the bottom and the sides of the lower parts of the carbon blocks *l l* are fastened in any suitable manner thin copper bars *e e*, which are curved outside the frame of the carriage in order to facilitate their connection with the conductors of the dynamo-

electric machine. The pieces by which the copper bars are fastened to the carbon blocks are arranged so that they can be made integral with the bottom of the carriage, so that the carbon blocks *l l* are integral on one hand with the copper bars *e e* conducting on the current and with the bottom of the carriage on the other.

The two carriages bearing the electrodes may, if this should be deemed necessary, be separated by a single central fusion-hearth *h*, the size of which would have to be varied according to the electric power to be used. This hearth would be made of bricks and would have no other purpose than to support the matter to be treated. Both carriages have metallic parts *g* by which they engage the cavities *i i*, provided in the hearth *h*, in order to prevent the conducting-bodies, as well as the mass in fusion, from dropping from the carriage. The fusion-hearth *h* is mounted on wheels which run upon rails located perpendicularly to those which sustain the electrode-carriages. (See Figs. 1 and 3.) The two carriages are connected with each other by a system of cables *n n* and pulleys *k k*, one of which has a crank *o* with a handle. In order to render the control of the cable still more secure, one could replace the controlling-pulley by a drum and wind the cable twice or thrice around this drum.

The upper part of the furnace is terminated by a refractory vault *p*, bearing a chimney *r*, allowing of the evacuation of the hot gases. Apertures *s s* are provided in the walls of the furnace in order to permit the electrode-carriages to be introduced into the furnace, whereafter the said apertures may be closed or not, as the case may be.

The working of the furnace is as follows: The two electrode-carriages being placed in the circuit between the two conductors of the dynamo-electric machine, as soon as the latter starts its work the current passes into the carbon blocks *l l*, which transmit the same to the small electrodes *d d*. Good care must be taken before starting the work that the two carriages, as well as the space between them, be covered with carbon or any other conducting material, which when the current passes therethrough is brought to a very high degree of incandescence. This is indicated at *y*. The second carriage makes the circuit and acts from an electrical standpoint exactly in the same way as the first one—that is to say, the electric current runs through the small electrodes *d d* and the carbon blocks *l l*, from whence it returns to the dynamo. By the imperfect contact between the small electrodes and the solid carbon blocks small electric arcs are produced at the junction of the same, and as the matter to be treated will not fail to be filtered through the layer covering the electrodes to this point of contact, and it will render this contact more perfect without, however, soldering the small electrodes completely on the carbon blocks. The matter to

be treated is introduced into the furnace through the openings *t t*, and a third opening *v* may be provided in order to serve as an outlet for the finished or treated mass. The regulation of the resistance is obtained by a simultaneous displacement of the two electrode-carriages, this displacement being obtained by means of turning the crank *o* in the direction required and according to the degree of resistance which it is desirable to obtain. If the crank is turned in the direction of the arrow *u*, the two carriages will run apart under the action of the cables, and if the crank is turned in the other direction the two carriages will approach each other. When the two carriages are drawn apart, this displacement will cause a break in the mass under treatment at the junctions of the two carriages with the central hearth, so that the break takes place in the zone of the greatest heat and where the mass under treatment has reached the highest degree of fusion. Therefore this point is also the best place for collecting or evacuating the mass finished to be treated. It follows that such a disposition of the furnace is the best for purposes of electrometallurgy, for it permits by the incandescence of the matter placed between the two junctions just spoken of of regulating the temperature which is then dependent on the electric currents employed. A special advantage of this arrangement is that it permits of avoiding the volatilization of matter whose temperature of fusion is not high. Moreover, the perturbations so detrimental in certain metallurgic processes and yet unavoidable with the ordinary furnaces on account of the presence of electrodes of carbon are also avoided with my furnace, as the matter under treatment is not brought into contact with the extremities of the carbons of the movable electrode bearings or carriages. In order to obtain this result, it would only be necessary, but also sufficient, to place on the upper extremities of the carbons of the carriages a conducting-body not susceptible of modifying industrially the composition of the matter to be treated. In this way the detrimental action spoken of above, and which consists in the carburization of the mass to be obtained, is sure to be avoided.

Whenever the metal or alloy to be obtained should not be carburized, it is clear that the layer *y*, serving to insure the passage of the current at the beginning of the operation, should not be of carbon, but of a conductor not susceptible of modifying industrially the composition of the material to be obtained, and this conductor will preferably be of the same material as that desired to be obtained or of a material that enters into the composition of this last. If, for example, it is desired to obtain chrome-iron, and this not to be carburized, the upper extremities of the carbons *d* of one of the movable carriages will be united with those of the other by a layer of particles of iron covering also the central hearth, and in any case the purpose of this layer,

whatever may be its composition, remains the same. The electrical connection is closed in beginning the operation through the layer *y*. When the conducting-body is brought to a sufficient temperature by the passage of the current, it is then that the furnace is charged with the material to be treated. The introduction of this material is made through the upper orifices *t t* and the side orifice *t*. The material is spread upon the carriages the same as the layer *y*. The withdrawal is through the spout *v*.

When the small electrodes are burned up, it is only necessary in order to replace them by new ones to draw the carriages from the furnace. As the surfaces of contact between the small electrodes and the carbon blocks whereon they rest are but small and as this contact between the two respective surfaces is only rendered solid through the products of filtration of the molten mass, it is easy to separate the small electrodes from the large carbon blocks, the cooling mass shrinking in an opposite direction from the carbon.

As the electrodes are constantly surrounded by a reducing medium, they, especially the parts *d*, suffer almost no deterioration whatever and are used up very slowly, and as they are of very small dimensions it is possible to use for this purpose the non-utilized break and waste of electrodes cast off by other branches of industry—for instance, the broken carbon sticks of arc-lamps—whereby an important result of economy is to be obtained in all manufacturing branches using electric furnaces. It will be well to mention that this system permits of preserving the big electrodes and of replacing only the smaller ones, for when the mass treated is taken away from the electrode-carriage the small electrodes only are bound up with the mass found ed when the latter has cooled. The electrodes instead of occupying the top of the carbon blocks, as shown by the drawings, could as well as these carbon blocks be placed on any other geometrical line—for instance, on a straight line parallel to the junctions of the carriages.

As the two movable electrode-carriages do

not require any openings in the furnace for the passage of the electrodes, as is necessary with the ordinary furnaces, my system permits of a complete closing of the electric furnace in all cases where it is desirable or necessary to exclude the air from operation or to operate under pressure.

It must be well understood that the furnace shown is only intended as one development of the invention and that the latter may be carried out in another form according to the different applications the furnace may be called upon to serve.

What I claim as my invention, and desire to secure by Letters Patent, is—

1. An electric furnace comprising a fusion-hearth *h* provided with cavities *i*, two electrodes inclined toward the fusion-hearth provided each with a tongue *g* entering one of the said cavities *i*, these electrodes being mounted on wheels running upon rails, and connected by means of cables *n n* bearing upon return-pulleys *k k* and passing around a drum *m* provided with a hand-crank *o*, the said fusion-hearth *h* being likewise mounted on wheels running upon rails disposed perpendicularly to the said rails of the said electrodes, substantially as shown and described.

2. An electric furnace comprising two electrodes mounted by means of wheels upon rails and united by means of cables bearing upon return-pulleys *k k* and passing around a drum *m* provided with a hand-crank *o*, each of these electrodes being composed of a carriage divided by means of small arches *a* in two parts of which the lower one is cooled by a current of air flowing through the chamber which accommodates the conductor *e* and its connections and the large carbon blocks *l l* which cross the said arches *a* and upon which are simply placed small electrodes *d*, the space around the latter being filled with powdered carbon, substantially as described.

Signed at Paris, France, this 19th day of November, 1900.

CHARLES ALBERT KELLER.
